COLLAPSIBLE WORK BENCH

Alan J. Solo, Brooklyn, N.Y., assignor to Creative Environments Inc., New York, N.Y., a corporation of New York

Filed July 12, 1967, Ser. No. 7,784

Term of patent 14 years

Int. Cl. D6—01

U.S. Cl. D33—14

FIG. 1

FIG. 3

FIG. 2

FIG. 4

FIGURE 1 is a side elevational view, partly broken away, of a collapsible work bench in erected condition showing my new design;

FIGURE 2 is an end elevational view thereof in fully collapsed condition;

FIGURE 3 is a side elevational view thereof in fully collapsed condition;

FIGURE 4 is a fragmentary view, partly in section, taken in the direction of the arrows 4-4 of FIGURE 3.

The dominant features of the design resides in the portions shown in full lines.

I claim:

The ornamental design for a collapsible work bench, substantially as shown and described.
